UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

MACHINE-SWITCHING TELEPHONE SYSTEM.

1,393,521.

Specification of Letters Patent. Patented Oct. 11, 1921.

Application filed April 27, 1917. Serial No. 164,870.

To all whom it may concern:

Be it known that I, CHARLES L. GOODRUM, a citizen of the United States, residing at New York, in the county of New York and 5 State of New York, have invented certain new and useful Improvements in Machine-Switching Telephone Systems, of which the following is a full, clear, concise and exact description.

10 This invention relates to machine switching telephone systems, and more particularly to improvements in group selecting switches for use in such systems.

The object of the invention is to provide 15 an arrangement for eliminating the trunk hunting interval in the operation of a group of a selecting switch.

A feature of the invention is the use of 20 switching means somewhat similar in construction to the well known Keith line switch (U. S. Patent No. 1,151,543), in a directly actuated selector switch.

Generally stated, the invention comprises 25 a plurality of banks of contacts, each bank being under control of a plunger, means for keeping the plungers always in operative relation with sets of contacts which are connected to idle trunks and a means for selectively actuating any one of said plungers.

30 Through such means an idle trunk is instantly available for the extension of a connection at the end of the group selecting operation, and the trunk hunting operation is entirely eliminated.

35 In the drawings, Figure 1 is a diagrammatical perspective view of a structure embodying this invention showing in part the necessary elements forming two switching mechanisms; Fig. 2 is a diagrammatical representation of a path through which a connection between two substations may be established, showing an indicated calling subscriber's substation, an indicated line switch, a group selector embodying this invention, 40 an indicated connector switch, and an indicated called subscriber's substation.

45 Each group selector switch consists essentially of a plurality of plungers, such as P^1 and P^2 , each placed in operative relation to a plurality of sets of contacts, such as C^1 and C^2 or C^3 and C^4 . Certain contacts in each set are common to the line L^1 , the other contacts being individual to the trunks, such as T^1 , T^2 , T^3 and T^4 , so that the actuation of the 50 plunger P^1 will connect the line L^1 to either

trunk T^1 or T^2 or the actuation of plunger P^2 will connect the line L^1 to either trunk T^3 or T^4 .

Trunks T^1 and T^2 belong to one group, while trunks T^3 and T^4 belong to another group. These groups are selected through the actuation of the primary magnet PM , which rotates the shaft 1 the number of steps corresponding to the first digit of the called subscriber's telephone number. The rotation of the shaft 1 brings a pin 3 or 4 in operative relation with a pin 5 or 6 associated respectively with the plungers P^2 and P^1 . At the end of the rotating movement of the shaft 1, the magnet 7 is actuated, and, 60 through its armature 8, presses on a disk 9 and moves the shaft 1 downwardly. A pin on the shaft, such as 3, is thereby brought into engagement with a pin, such as 5, associated with a plunger, such as P^2 , which, 65 engaging the contacts, such as C^3 , connects the line L^1 with the trunk T^3 . The trunk T^3 now having been made busy, the magnet 7 is actuated in a manner to be described hereinafter, and allows the rotation 70 of the plunger bar 11 on its axis, so as to bring another plunger, such as P^4 , still in engagement therewith, into operative relation with another set of contacts connected with an idle trunk. 75

When the plunger bar 11 has been rotated through its full arc, means, hereinafter to be described, cause the energization of magnet N , whereby the bar 11 is returned to the position shown or normal. 80

It is thought that the invention may be more fully understood through a description of the establishment of a connection employing a group selecting switch of this nature.

Referring especially to Fig. 2, S^1 represents the calling subscriber's substation. When the receiver is removed from its hook, the connection will be extended to the group selector through a line switch indicated at LS in the well known manner, whereupon 95 a circuit will be established from battery, the left-hand winding of relay LR , the normal contact of SON^1 , through the circuits of the line switch and the substation S^1 to the normal contact of SON^2 , the right-hand 100 winding of relay LR to ground. Relay LR becomes energized in this circuit and attracts its armature, whereupon a circuit is established for the energizing of the first slow relay FS from ground, armature and 105 110

alternate contact of relay LR, winding of relay FS to battery and ground.

When, now, the subscriber at substation S^1 manipulates his sender, the resulting series 5 of breaks in the circuit through which relay LR is energized cause the intermittent de-energization and energization of relay LR and a consequent vibration of its armature. Upon the first retraction a circuit is estab- 10 lished from ground, the armature and normal contact of relay LR, the armature and alternate contact of relay FS, the lower armature and contact of relay 7 to a point where the circuit divides, extending in one 15 direction through the winding of the second slow relay SS to battery and ground, and in the other direction through the winding of primary magnet PM to battery and ground. Slow release relay SS becomes en- 20 ergized and holds its armature attracted until after the last impulse has been received and its circuit is permanently opened. Relay PM, however, responds to each sep- 25 arate impulse, and, in the manner before described, rotates the shaft 1, whereby a group of trunks is selected.

Shortly after the receipt of the last impulse, the second slow relay SS retracts its armature and establishes a circuit from 30 ground, the armature and contact of relay SS, the primary off-normal contact PON¹ through the upper winding of relay 7, the brush B, contact 12, upon which the brush B has been set by the rotation of shaft 1, to the 35 contact and right-hand armature of relay 10, the normal contact and left-hand armature of relay 13 to battery and ground. Relay 7 becomes energized in this circuit and causes the plunger to operate the contacts C 40 in the manner heretofore described. At the same time relay 7 attracts its armatures, opening at its lower armature and contact the circuit through which relays SS and PM were energized, and completing through 45 its inner armature a holding circuit for itself, extending from ground, battery, the lower winding of relay 7, the inner armature and contact of relay 7, the left-hand armature and contact of release relay R to ground. 50 The movement caused by the energization of relay 7 operates the secondary off-normal contacts SON¹, SON² and SON³, whereby the calling line is extended through the contacts C to the trunk T, and thence to the connector switch CS. A further manipulation 55 of the sender at the substation S^1 directs the operation of a connector switch CS to the terminals of the called line S^2 , whereby the connection between these two substa- 60 tions is completed.

When the set of contacts C was operated a ground was extended through the springs 65 14 and 15 to the conductor 16, and thence to the first contact 17 and brush 18, whereby it was further extended through the contact

and left-hand armature of relay 10, winding of relay 10 to the normal contact and left-hand armature of relay 13 to battery and ground. Relay 10 becomes energized in this circuit and escapes the plunger bar 11 into 70 its next position, whereby the brush 18 is brought into operative relation with the next contact 19.

The brushes 18 and 20 attached to the bar 11 form a master switch arrangement whose 75 function is to keep the plungers P² and P⁴ before an idle trunk. Thus when contact 17 is connected to ground in the manner de- 80 scribed, the brush 18 is caused to move into engagement with contact 19 which is asso- 85 ciated through a conductor similar to 16 with the next idle trunk.

In the normal position of the plunger bar 11 the brush 20 rested on a contact 21, where- 90 by a connection was established between 85 ground, the brush 20 and contact 21, the winding of relay 22 to battery and ground. As the plunger bar 11 is escaped into its second position, this circuit is broken, and the relay 22 is deenergized. When the plun- 95 ger bar 11 is finally escaped into its last position, the brush 20 comes into association with the contact 23, whereupon ground is projected from brush 20 through contact 23, the winding of relay 13 to battery and 100 ground. Relay 13 becomes energized in this circuit and establishes a holding circuit for itself from ground, the armature and contact of relay 22, the right-hand armature and contact of relay 13, and thence over the 105 circuit previously traced. A connection is at the same time established from ground, battery, left-hand armature and alternate 110 contact of relay 13, the winding of magnet N to ground. Magnet N is thereupon held 115 energized until under its action the plunger bar 11 has been returned to its normal position and brush 20 is again brought into associa- 120 tion with contact 21. This action results in the energization of relay 22, the conse- 125 quent breaking of the holding circuit of relay 13, and the retraction of the armatures of relay 13.

The release of this switch is accomplished through the projection of ground over the 115 release trunk of the established connection in the well known manner, whereby the relay R becomes energized and opens the holding circuit of the relay 7 at its left-hand armature and withdraws the pawl 24 from 120 the driving ratchet wheel 25 through which the shaft 1 has rotated. The retraction of its armatures by relay 7 allows the shaft 1 to move upward and removes the force which keeps the plunger, such as P², in associa- 125 tion with the contacts such as C³.

What is claimed is:

1. In a telephone system, telephone lines, groups of extending circuits, selective switches for interconnecting said lines and 130

- said circuits comprising terminals in which said lines terminate, terminals arranged in operative relation to said line terminals in which said circuits terminate, a means for causing the operative interconnection of said line and said circuit terminals individual to each said group of extending circuits, means common to said groups for controlling said means and means for selectively operating 10 said first means.
2. In a telephone system, a line, a plurality of groups of trunks, an automatic switch for establishing connection between said line and an idle one of said trunks provided with 15 contacts in which said line and said trunks terminate, a series of members for operatively associating said line terminals with said trunk terminals, each said member being individual to one of said groups of 20 trunks, trunk controlled means for operatively associating said members with sets of terminals connected to idle trunks, and line controlled means for selectively operating said members.
- 25 3. In a telephone system, a line, a plurality of groups of trunks, an automatic switch for establishing connections between said line and said trunks comprising terminals in which said line terminates, terminals arranged in operative relation with said line terminals in which said trunk terminates, means individual to each of said
- groups of trunks for actuating said terminals, trunk controlled means for automatically associating said means with an idle 35 one of said trunks, and line controlled means for selectively operating said terminal actuating means.
4. In a telephone system, telephone lines, groups of extending circuits, automatic 40 switches for interconnecting said lines and circuits, groups of spring contacts in which said lines and said extending circuits terminate, means individual to each said group for operatively actuating said spring contacts to interconnect said lines and said 45 circuits, means common to said groups for automatically associating said means with contacts connected to an idle one of said circuits, and line controlled means for selectively 50 actuating said contact actuating means.
5. In a telephone system, a selective switch comprising a plurality of groups of banks of contacts, means individual to each bank 55 for operating the contacts thereof, means common to each group for controlling said first means and means individual to the corresponding bank of each group for selectively operating said first means.

In witness whereof, I hereunto subscribe my name this 26th day of April A. D., 1917.

CHARLES L. GOODRUM.
